UNITED STATES PATENT OFFICE

2,067,037

CROSSING SLAB

Earl C. Alexander, Glen Ellyn, Ill., assignor to
Massey Concrete Products Corporation, Chi-
cago, Ill., a corporation of Virginia

Application May 6, 1936, Serial No. 78,130

4 Claims. (Cl. 238—8)

The present invention relates to crossing slabs, and is particularly concerned with improved crossing slabs and arrangements for installations of crossing slabs for making a right angled rail-way crossing or a skew crossing.

One of the objects of the invention is the provision of an improved crossing slab construction which is absolutely safe from the point of view of possibility of teetering of the slabs on intermediate ties and from the point of view of securing of the slabs in place by securing devices or interlocking devices so as to make sure no slab will ever project upwardly so that it might be struck by a passing train.

Another object is the provision of an improved slab construction peculiarly adapted to be used with improved securing devices, and which may be manufactured and installed more economically than the devices of the prior art.

Another object of the invention is the provision of a plurality of improved methods of installation of crossing slabs of the class described and the provision of an improved construction of crossing slabs which does not require the use of armor about the edges of the slab to protect the edges against breakage.

Other objects and advantages of the invention will be apparent from the following description and the accompanying drawings, in which similar characters of reference indicate similar parts throughout the several views.

Referring to the drawings, of which there are three sheets,

Fig. 1 is a fragmentary plan view of a right angle railway crossing equipped with slabs constructed and installed according to the present invention;

Fig. 2 is a fragmentary plan view of a skew crossing;

Fig. 3 is a sectional view taken on the line 3—3 of Fig. 1, located in the direction of the arrows;

Fig. 4 is a fragmentary sectional view taken on the plane of the line 4—4 of Fig. 1, the view being enlarged over that of Fig. 1;

Fig. 5 is a fragmentary sectional view, taken on the plane of the line 5—5 of Fig. 1, looking in the direction of the arrows;

Fig. 6 is a fragmentary top plan view showing a securing device installed at the adjacent four corners of four slabs;

Fig. 7 is a fragmentary top plan view showing a securing device installed midway in the side of one slab;

Fig. 8 is a transverse vertical sectional view

through a modification showing another mode of installing and securing the slabs;

Fig. 9 is a similar view of another modification;

Fig. 10 is a fragmentary sectional view, with the slabs in elevation, showing another mode of securing the slabs to a tie;

Fig. 11 is a top plan view of a fragment of the installation of Fig. 10;

Fig. 12 is a fragmentary sectional view taken through a rail and the adjacent slabs, showing details of construction of the installation to form flange-way guards;

Fig. 13 is a view similar to Fig. 12 of another modification.

Referring to Fig. 1, the crossing, which is indicated in its entirety by the numeral 10, is shown in connection with the usual ties 11 and rails 12, 13. The slabs in the installation of Fig. 1 are of three different types, such as the edge slabs 14, the slabs 15 adjacent the rails on the inside, 20 and the center slabs 16.

The concrete slabs preferably comprise pre-molded concrete members, generally rectangular in plan and in elevation, except for the provision of formations to accommodate the tie plates, rail flanges, and fastening devices.

All of the slabs are preferably provided with reinforcing rods extending longitudinally and transversely, and various forms of reinforcing may be used, according to standard practice.

Referring to Fig. 4, the slabs preferably extend longitudinally of the track and preferably extend over the space between more than two ties. Thus, the slab 15, shown in Fig. 4, extends from the tie 17 to the tie 19 and traverses the tie 18. It is preferably cut out at 20 and 21 adjacent each end so as to provide a seating surface for engaging the ties 17 and 19, leaving the downwardly projecting portions 22, 23 engaging between the ties. The shoulders 24—27 serve to keep the slabs in proper position with respect to the ties, and the groove 28 between the shoulders 25 and 26 is deeper than the other indentations adjacent shoulders 24 and 27 so that the tie 18 does not touch the slab 15. Thus, the slab is supported at both ends and there is no chance of it teetering on intermediate ties.

It should be understood that in other embodiments of the invention slabs may be made long enough to span more than two tie spaces, in which case they would rest only on the ties which are adjacent the ends of the slabs.

The preferred form of reinforcing is shown in elevation in Fig. 4, with rods 29 extending transversely near the bottom of the slab, and other

rods 30 extending longitudinally of the slab near the bottom, and having downwardly bent ends 31 near the top.

In the embodiment of Figs. 1 and 3, it will be observed that the edge slabs 14 are mortised at 32 to provide space for the tie plates 33, the lower rail flanges, and the railway spikes 34. The same is true of that edge of the slabs 15 which is adjacent the rails.

10 In addition to this, the slab 15 is formed with a right angular groove 35 adjacent the rail in order to provide space for the wheel flange. The other edges of the slabs may be plane surfaces, which are rectangular in elevation, so that the 15 slabs fit flatly against each other to form the complete crossing.

In some embodiments of the invention the slabs may be secured in place solely by virtue of their weight and by the engagement of the shoulders 24-27 with the ties. In other embodiments of the invention the installation may be made safer by using securing devices such as the lag screws 36 (Fig. 3) which are located in grooves and sockets formed at the edges of the slabs and 25 screwed into the ties.

The grooves in the slabs may comprise tapered grooves 37 (Fig. 5) communicating at each end with the larger tapered sockets 38 which are adapted to receive the washer 39 and head 40. 30 When two slabs are arranged with their edges touching each other, a pair of the grooves 37 and sockets 38 form a bore and counterbore extending through the assembly for receiving the lag screw and washer. The head 40 and washer 39 are thus disposed below the surface, and one lag screw 36, by virtue of the washer and the formation of the grooves in the slabs, is adapted to hold down two or more slabs. Thus, in Fig. 1, the edge slabs have the lag screw grooves formed 40 midway between the side edges of the slabs, and one lag screw secures the two adjacent ends of two slabs to the tie.

With the slabs 15 and 16 between the tracks, the grooves are formed in the corners of the slabs 45 and comprise one-fourth of the cylinder, so that one lag screw 41 (Fig. 1), disposed at the four adjacent corners of four slabs, secures all of those slabs to the tie.

It should be understood that it is not necessary 50 to place lag screws at every corner or intersection between the slab joints, but only at the two diagonally opposite corners.

In the embodiment of Fig. 2, it will be noted that the skew crossing is formed by offsetting 55 the joints between the slabs, and in such case the lag screws 42 are at two corners and midway between the ends of the other slab. Here the slab 15 has a tapered groove formed in its edge, while the two corners have grooves which are 60 equivalent to a quarter of the aperture.

Supplementing the lag screw securing device, the rails may be provided with bores 43, with headless bolts 44 secured therein by lock nuts 45, the bolts projecting from each side of the rail. 65 The slabs may then be provided with tapered bores 46, 47 on the sides adjacent the rail, and the ends of the bolt 44 project into these tapered apertures and prevent the slabs from being lifted 70 out of place at the edge adjacent the rail. This feature may be used with or without the lag screws, as in some embodiments of the invention it may be deemed necessary only to make sure that the slabs are held down adjacent the rails. 75 Figs. 6 and 7 show enlarged detail views of the

sockets which are formed in the corners and edges of the slabs for receiving the washers 39.

Referring to Fig. 8, this is a modification in which the slabs are held down principally by the 5 securement of the center slab 48. In this embodiment the center slab has a socket 49 and bore 50 for receiving the head, washer and screw bolt which is secured into the tie below that slab.

The center slab 48 has a laterally projecting flange 51 at each side, which overlies a laterally 10 projecting lower flange 52 carried by the slabs 53, 54. It will thus be observed that the center slab is adapted to hold down the slabs 53, 54 by virtue of the engagement of the flanges 51 with the flanges 52, greatly reducing the number of 15 securing devices which would otherwise be needed.

Fig. 9 shows another modification, in which the side slabs 55, 56 have such flanges for holding 20 down the center slab 57.

Fig. 10 shows another modification, in which 20 the edges of the slabs are provided with right angle-shaped grooves 58. These grooves extend into the slab from the edge face thereof, so that the securing rods 59, which have a complementary right angular end 60, may be slid into the 25 groove 58 in a lateral direction. The lower angular bend 61 on the rod 59 engages below the tie 62 where it is held by virtue of the engagement 30 of the upper end of the rod in the groove 58. In this case no securing devices are visible from 35 the top of the crossing, thereby making it more difficult for unauthorized persons to remove the slabs.

Referring to Fig. 12, this is a fragmentary view 35 of an installation having an improved method of closing the spaces between the slabs and the rail, and forming a groove for the wheel flange. In this case the edge of the slab adjacent the rail is provided with an angle iron having a vertically 40 extending flange 63 and a horizontally extending flange 64. Tapered anchoring lugs 65 may be punched out of the horizontally extending flange, and that flange and the lugs may be embedded in the concrete in such manner that the flange 63 is spaced from the edge of the concrete 45 by a distance equal to the thickness of flange 63. A second angle iron 66 may have its vertical flange confined between the concrete and the flange 63, and it may have its horizontal flange 50 closing the space between the concrete and the rail.

The angle irons are preferably so located that the horizontal flange of the angle iron comes immediately below the top flange of the rail, on the 55 outside of the rail. The slab on the inside of the rail may be equipped in a similar manner with angle irons 67 and 68, except that both these angle irons are located slightly lower, so as to 60 clear the wheel flange and to cause the upper surface of the angle iron flange 68 to be substantially flush with the horizontal concrete surface 69.

Referring to Fig. 13, this is a modification in which the edges of the concrete slabs adjacent the rail have been provided with Z bars 70, 71 of 65 such width as to locate their upper horizontal flanges in substantially the same position as in Fig. 12. These Z bars may be anchored to the concrete slabs by suitably tapered lugs 72 punched out of the web, or by any other suitable 70 form of anchor.

While I have illustrated a preferred embodiment of my invention, many modifications may be made without departing from the spirit of the invention, and I do not wish to be limited to the 75

precise details of construction set forth, but desire to avail myself of all changes within the scope of the appended claims.

Having thus described my invention, what I claim as new and desire to secure by Letters Patent of the United States, is:

- 5 1. In a crossing slab, the combination of a pre-molded cementitious member having sides of regular polygonal form, said member being formed at one of its edge surfaces with a partially cylindrical groove adapted with other similar members to form a recess in a crossing installation for a securing member, said cementitious member having said groove formed at one of its corners whereby a multiplicity of said members meeting at said corner may be secured by a single securing member.
- 10 2. In a railway crossing, the combination of a rail having a rod fixedly carried by the web of said rail and projecting laterally from said rail, with a crossing slab arranged with one edge face parallel to said rail, said edge face having a socket for said rod to anchor said crossing slab against vertical removal.
- 15 3. In a railway crossing, the combination of a rail having a rod fixedly carried by the web of said rail and projecting laterally from said rail, with a crossing slab arranged with one edge face parallel to said rail, said edge face having a socket for said rod to anchor said crossing slab against vertical removal, said edge face having a socket 5 for said rod to anchor said crossing slab against vertical removal, said apertures being tapered to provide sufficient clearance for said rod in said aperture when the opposite edge of said slab is lifted above adjacent slabs to effect a removal of 10 said slab.
- 20 4. In a railway crossing installation, the combination of a railway comprising a pair of rails supported by a plurality of ties, a plurality of crossing slabs, said slabs extending longitudinally 15 of the railway and spanning the spaces between a plurality of ties, said slabs being formed with grooves adjacent each of the ties under the slabs, the bases of the grooves at the slab ends forming supporting surfaces and the grooves intermediate 20 the slab ends being deeper to prevent contact with intermediate ties.

EARL C. ALEXANDER.
